UNITED STATES PATENT OFFICE.

AUGUST S. LISS, OF CHICAGO, ILLINOIS.

FLY EXTERMINATOR.

Application filed August 5, 1921. Serial No. 490,068.

To all whom it may concern:

Be it known that I, AUGUST S. LISS, a citizen of the United States, residing at Chicago, in the county of Cook and State 5 of Illinois, have invented certain new and useful Improvements in Fly Exterminators, of which the following is a description.

My invention relates to improvements in exterminators, and more particularly to an 10 exterminator for the destroying of insects and vermin, especially flies.

One of the objects of my invention is to provide a fly exterminator that may be placed out of the reach of children so that 15 they can not be injured by the poisonous constituents thereof.

Another object of my invention is to provide means for keeping the poison paper of the exterminator properly moistened over 20 long periods of time by providing a liquid reservoir and moisture-conducting means leading therefrom to the paper.

It also has as an object the production of a 25 filler element or cartridge which may be distributed as a mist, and safely handled and without loss of strength or efficiency.

The invention has among its other objects the production of a device of the kind described which shall be neat, ornamental, 30 compact, durable, reliable, efficient and satisfactory for use wherever found applicable.

Many other objects and advantages will be obvious to those skilled in the art from the disclosure herein given.

To this end my invention consists in the 35 novel construction, arrangement and combination of parts herein shown and described, and more particularly pointed out in the claims.

In the drawings, wherein like reference 40 characters indicate like or corresponding parts,

Fig. 1 is an elevation of my improved device;

Fig. 2 is a vertical section therethrough taken on the line 2—2 of Fig. 1;

Fig. 3 is a section taken substantially on the line 3—3 of Fig. 1; and

Fig. 4 indicates one of the fillers or 45 renewal cartridges.

In the drawings, wherein I have illustrated the preferred embodiment of my invention, there is shown a casing 1 made of any suitable size, shape and material, preferably of perforated or reticulated material, such as punched sheet metal or screening,

the perforations being indicated at 2. The casing 1 is tubular or hollow, both its ends being adapted to receive closure plates or caps 3 and 4, said caps being secured thereto 60 in any suitable manner, as by screw-threading, frictional engagement or by any other equivalent means for the purpose. One or both of said closures may be made removable for the insertion of the cartridge or for 65 cleaning purposes, as will be hereinafter described.

The lower cap 4, as shown in Fig. 2, has a reservoir 8 formed therein for the storage of surplus water or any other desired liquid. 70 A sheet of material 5, for example paper or the like, preferably impregnated with a poisonous compound, is removably inserted into the casing so that the flies may have access thereto through the apertures 2. As 75 the poisonous constituents of the sheet 5 are generally active only when the same is moist, I provide means for keeping said paper moist over a considerable period, said means comprising a body of absorbent 80 or porous material 6, which may be of felt, sponge, excelsior, waste or other suitable animal, vegetable or mineral material having porous or absorbent properties so that said material will conduct the moisture from 85 the liquid in the reservoir 8 to the paper 5 and keep it in moist and active condition. The exterminator may be hung at suitably convenient places, such as on chandeliers, screens, curtains, shelves, fixtures, or the 90 like by means of a hanger or hook 7 suitably secured to the casing, or equivalent means, as shown. The absorbent material may be initially moistened by immersing the assembled casing and parts in a body of water, 95 or other liquid, or, if desired, either the top or bottom caps may be removed and water placed therein.

If it is desired to use the casing for one or more seasons, as would be the case where 100 the parts are ornamental and comparatively expensive, I have provided renewal cartridges or refills, as shown in Fig. 4, in which the poisonous sheet is formed to the desired size and shape, and has the absorbent material 6 interiorly thereof. When it is desired to insert the cartridge into the casing, one or both of the caps 3 or 4 are removed to allow said insertion and replaced after it has been inserted. If the device is 110 hung upright, the lower cap will catch and retain all surplus water or drippings. The

cartridge may be immersed, after using, in poisoned liquid to keep the same potent or active. It is to be understood that the exterminators may be made as ornamental or decorative as desired so as to conform to the designs and colors of the surroundings in which they are arranged. Where a cartridge is not at hand, one may be readily made by the user and employed. It will be noted that the poison material may be kept moist without having a surplus liquid that will spill and flow over drapes, carpets, floors, shelves, or other articles. Also, owing to the convenient construction and the suspending means, the same may be hung, suspended or supported at any convenient point, out of the reach of children or pet animals, and also in places where flies may gather or congregate, for example, on chandelier fixtures, shelves, curtains, picture frames, etc.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In an insect exterminator, a perforated

casing, poisonous material arranged therein and accessible from the exterior thereof, a reservoir adapted to contain a liquid, and moisture-absorbent means above and leading from said reservoir and communicating with said poisonous material for keeping it in a moist condition.

2. In an insect exterminator, a casing having apertures through the walls thereof, removable closures for the ends of said casing and forming liquid reservoirs, a poisonous material in said casing accessible through said apertures, and a porous material within said casing and leading from said reservoirs to said poisonous material to conduct moisture thereto.

3. In an insect exterminator, a casing having apertures through the walls thereof, removable closures for the ends of said casing forming a reservoir refillable from either end of the casing, absorbent poisonous material removably arranged in said casing accessible through said apertures, and a porous material removably arranged in said casing leading from said reservoir to said poisonous material to conduct moisture thereto.

In testimony whereof, I have hereunto signed my name in the presence of two subscribing witnesses.

AUGUST S. LISS.
